UNITED STATES PATENT OFFICE.

ROBERT R. PAGE, OF NEW YORK, N. Y.

TOP ADJUSTABLE BANJO TAILPIECE.

Application filed May 4, 1923. Serial No. 636,600.

The present invention relates to an improvement in tail pieces for banjos and has for its object amongst others the accomplishment of greater economy in construction, 5 lighter weight and above all greater ease of adjustment for increasing or decreasing the total pitch of the banjo at will.

Another very important object is the simplicity of the means whereby the aggregate 10 tensioning of all of the strings on the musical instrument simultaneously is accomplished in a better manner than has heretofore been done.

The most important advantage of my construction however, relates to the modification 15 of the tail piece structure whereby upon release of the string tensioning means, which also acts as a cover for the tail piece, is the manner in which the spring tensioned cover 20 raises itself to uncovering position, thereby exposing the tail piece portion, which is so constructed as to enable the player to readily remove or replace strings upon the string posts thereof with the greatest of ease.

25 I attain these objects and such other objects as may appear during the subjoined description by way of example, of one of the possible embodiments of the invention shown in the accompanying drawing forming part of this specification in which Figure 1, is a fragmentary top or plan view of the head of a musical instrument and a top or plan view of the tail piece operatively attached to the head.

35 Figure 2, is a fragmentary side view of the head of a musical instrument and a side view of the tail piece operatively attached thereto, the tail piece being in partially open or uncovering position whereby the pressure 40 of the tensioning portion thereof is relieved from the strings of the instrument.

Figure 3, is a view similar to Fig. 2, except that the tail piece is shown in closed or covering position, the tensioning portion 45 thereof exerting pressure on the strings of the instrument for tensioning the strings.

Figure 4, is a side elevation of the tail piece, in partially open or uncovering position, and just prior to movement of the cover 50 portion to completely open position.

Figure 5, is a top or plan view of the tail piece in the partially open or uncovering position shown in Fig. 4, and

55 Figure 6, is a top or plan view of the tail piece, the cover portion having been moved to completely open position.

Similar reference characters denote similar parts throughout the several views.

The tail piece comprises in its main parts the base generally denoted by 10, and the 60 tensioning cover generally denoted by 11, and is made of any suitable metal or material.

The base 10 comprises the rectangular mid portion 12 having the side portions 13 and 14 provided with the extended apertured ends 15 and 16. The mid portion 12 has on its inner edge the rigidly upstanding rearwardly turned hook 17, and has suitably located on its upper surface the string pins 18. 70

The mid portion 12 has on its outer edge the angular bracket 19, having the outwardly bent reduced end 20, the bracket 19 as shown being part of the mid portion 12 between the extended ends 15 and 16 bent downwardly 75 at a right angle to the plane of the mid portion. The end 20 has an aperture therein which receives the screw threaded bolt 21 retained in this aperture by engagement of the head of the bolt with the end 20, the free end of the bolt passing through the lug 22 on the shell or side of the musical instrument and held by the upper stop nut 23 and the lock nut 24, whereby the tail piece is retained in operative position on the instrument. 80

85 The cover 11 comprises the covering portion 25 and the tensioning end 26, the tensioning end 26 being that portion of the cover extending inwardly from the covering portion 25 from about the line of the inner edge of the base 10 when the cover is in closed or covering position, the term inwardly here and elsewhere herein meaning towards the musical instrument when the 90 tail piece is in operative closed position thereon.

95 The covering portion 25 has therethrough the rectangular slot 27 with which the hook 17 engages or passes through. The covering portion 25 has at its sides adjacent to its outer edge the apertured ears 28 and 29, overlapping the extended ends 15 and 16 of the base member, the aperture of the ear 28 as shown being threaded for receiving the 105 threaded end of the bolt or shaft 30, the bolt or shaft 30 passing through the ears 28 and 29 and extended ends 15 and 16, and the cover 11 being pivotably movable thereon. The bolt or shaft 30 has arranged thereon 110 the helix spring 31, one end 32 of which bears against the upper surface of the mid

portion of the base 10 and the other end 33 of which bears against the under surface of the covering portion 25, the tendency of this spring being to throw or move the cover 11 from closed to open position. The covering portion 25 has thereon the cam member 34 which consists of a substantially semi-circular wall portion 35 having a cam face 36, and a manipulating arm 37, the cam member 10 being secured for pivotal movement by the rivet pin 38 to the covering portion 25 of the cover 11, and being restricted in this movement in either direction by contact of the arm 37 with the stop lug 39 on the upper 15 surface of the covering portion 25.

The tensioning portion 26 for a portion of its length is in the same plane as the covering portion 25, and is then bent downwardly as at 40, Fig. 4, and then curved upwardly, as at 41, at its inner edge for the purpose later stated. The combined length of the covering portion 25 and tensioning portion 26 is such as to bring the curved end 41 substantially midway of the distance on 20 the strings of the instrument from the bridge 42 to the string posts 18 of the tail piece, when the tail piece is in operative position on the instrument.

When the tail piece is in operative position on the instrument, the strain of the strings on the string posts causes the curved end 41 to bear down upon the strings transversely thereof with a tensioning effect upon the strings for changing the pitch; 35 and it will be noted that the arrangement of the string pins 18 on the base portion 10 is such that the strings when secured thereto are in the same equally spaced parallelism that they are at the bridge 42 of the instrument, thereby providing a straight line tension or pull on the strings from the string pegs, not shown, to the string pins 18, and that the cover 11 at its end 41 is of sufficient width to engage transversely and exert pressure on all the strings while they are in this 40 equally spaced parallel relation, the cover 11, when in this position covering the string pins 18 and rendering them inaccessible for securing the strings thereto, until the cover is released from covering position and is moved by the spring 31 to uncovering position.

In operation.—The tail piece being attached to the instrument as described, the cover being in open or uncovering position, the strings are secured to the string posts and properly tuned; the cover 11 is moved into covering position, the end of the hook 17 of the base 10 passing through the slot 27 of the cover, the relative positions of cover and base being as shown in Fig. 5; by turning the manipulating arm of the cover the cam member 35 is caused to pass under the end of the hook 17 and by continuing to turn the manipulating arm 37 towards a position at right angles to its former position

the hook 17 rides up on the cam face of the cam member 35 and holds the cover firmly down in closed or covering position, Fig. 1, the strain of the strings on the string posts 18 conduced to this, and the end 41 of the cover bearing down transversely on the strings and tensioning them.

In the event of breaking a string, the manipulating arm 37 is moved to the position shown in Fig. 5, and the cover 11 allowed to move or fly up to open position, thus exposing the ends of the strings on the string posts, and the new string can be attached and the cover returned to its former tensioning position without disturbing the other strings, the pitch of the strings being the same as it was before movement of the cover.

Having thus described my invention, it should be understood that there may be modifications thereof and variations therein without departing from the spirit of the invention or exceeding the scope of the appended claims.

What I claim and desire to protect by Letters Patent is:

1. In a tail piece for musical instruments having strings, in combination, a base portion secured to the instrument, a pivotally supported covering member spring maintained in uncovering position and movable to covering position and when so moved extending over the base portion and engaging the strings of the instrument for tensioning the strings, and means including rotatably movable means cooperating between the covering member and base portion for retaining the covering member in covering position and releasable for permitting spring actuated movement of the covering member to uncovering position.

2. In a tail piece for musical instruments having strings, in combination, a base portion secured to the instrument, a covering member yieldably supported in uncovering position and movable from uncovering position to covering position and when in covering position extending over said base portion and having an end portion adapted for engaging the strings of the instrument for tensioning the strings, and rotatably movable means on the covering member engageable with means on said base portion for retaining the covering member in covering position and disengageable from said means on the base portion for permitting movement of the covering member to uncovering position.

3. In a tail piece for musical instruments having strings, in combination, a base portion secured to the instrument, a covering member pivotally secured at an end thereof to an end of the base portion and spring maintained in uncovering position and movable to covering position and when so moved

- extending over the base portion and engaging the strings of the instrument for tensioning the strings, and means including rotatably movable means cooperating between 5 thereto in the same spaced parallelism as the 45 parallelism of said strings on said bridge, a covering member spring maintained in uncovering position and movable from uncovering position to covering position and when so moved extending over said plate 50 and covering said string attaching means and having an end portion adapted for engaging the equally spaced parallel strings for tensioning the strings, and means on the covering member engageable with means on 55 said plate for retaining the covering member in covering position and disengageable from the means on said plate for permitting spring actuated movement of the covering member to uncovering position. 60
- 10 4. In a tail piece for musical instruments having strings, in combination, a base member secured to the musical instrument and having a portion thereof extending over the face of the instrument provided with an upstanding hook, and a covering member secured to said extending portion and movable from uncovering position to covering position and when in covering position disposed over said extending portion, said covering 15 member being spring maintained in uncovering position and having an opening therethrough and a rotatable cam member adjacent to said opening and having an end portion for transversely engaging the strings 20 of the instrument when the covering member is in covering position, said hook when the covering member is moved to covering position passing through said opening and being engageable with said cam member by 25 rotation of the cam member in one direction for retaining the covering member in covering position and being disengageable from the cam member by rotation of the cam member in reverse direction for permitting spring 30 actuated movement of the covering member to uncovering position. 35
5. In a tail piece for musical instruments having strings and a bridge adapted for supporting the strings in spaced parallelism thereon, in combination, a base portion secured to the instrument and including a plate extending inwardly over the face of the instrument and having on the upper face of 40 said plate means for attaching said strings thereto in the same spaced parallelism as the parallelism of said strings on said bridge, a covering member spring maintained in uncovering position and movable from uncovering position to 45 covering position and when so moved extending over said plate and covering said pins and having an end portion adapted for transversely engaging the equally spaced parallel strings, and a rotatable cam on the 50 covering member engageable with said hook for retaining the covering member in covering position and disengageable from said hook for permitting spring actuated movement of the covering member to uncovering 55 position. 65

ROBERT R. PAGE.
